Primary Examiner—Prabhakar Deshmukh
Attorney, Agent, or Firm—Charles C. Logan II[57] **CLAIM**

The ornamental design for a four-port controller tap for video games, as shown and described.

DESCRIPTION

FIG. 1 is a front perspective view of the novel four-port controller tap for video games;

FIG. 2 is a rear elevation view thereof taken along lines 2—2 of FIG. 3;

FIG. 3 is a top plan view thereof;

FIG. 4 is a left side elevation view thereof taken along lines 4—4 of FIG. 3 and the right side elevation view would be identical except that it is reversed;

FIG. 5 is a rear elevation view thereof taken along lines 5—5 of FIG. 6;

FIG. 6 is a bottom plan view thereof; and,

FIG. 7 is a front elevation view thereof taken along lines 7—7 of FIG. 6.
